UNITED STATES PATENT OFFICE.

ADRIAN FRANCIS SYKES, OF NEW BARNET, ENGLAND.

REPRODUCING AND RECORDING OF SOUND.

Application filed November 16, 1920, Serial No. 424,421, and in Great Britain November 18, 1919.

This invention relates to apparatus for the conversion of sound into equivalent variation of electric currents or potentials and to the conversion of electric currents or derivatives thereof into mechanical vibration for the purpose of reproduction.

The primary object of my invention is the production of phonograph or gramophone records of improved fidelity in which tonal purity, definition and beauty are enhanced while disturbances, false tones and blasts are minimized and in general in which defects usually attributed to the natural tones of diaphragms and the resistance of the wax to impression are eliminated.

In the full practice of my invention I employ a primary detector of a non-resonant nature which serves to derive electric potentials from sound waves, a system for modifying or distorting the wave forms of the potentials so derived and a powerful thermionic relay for the purpose of amplifying the effects in order that they may be large enough to operate a special recording device which is either in fact or in effect non-resonant. Sound is caused to vibrate a collecting mass of material either in fact or in effect devoid of tones and a coil immersed in a magnetic field or a microphone serves to detect the vibration; the electric currents derived in this way are distorted by means of the thermionic valve and inductances or by a condenser system or by both in combination; the distorted currents are then circulated in an inert coil of wire situated in a magnetic field to which coil is attached an engraving jewel in contact with a wax blank. The distortion required depends on circumstances as will be evident later. It is sometimes desirable to make use of a mechanical system with one tone or period of vibration and to make provision for eliminating the influence of this tone as will be described.

It will be convenient to deal with the problem of the derivation of electric currents equivalent to sound waves or systematically differing therefrom and the problem of engraving mechanical equivalents of electrical oscillations or systematic derivatives thereof separately and then to make some remarks on their use in combination.

Thus as regards detection my invention consists in allowing sound to vibrate a plain

mass freely supported; to the mass is rigidly attached an electrical conductor immersed in a magnetic field—a winding or coil; the electrical conductor is immersed in a magnetic field so that when the conductor vibrates an electromotive force is induced. If this E. M. F. is differentiated electrically the result is a practically true replica of the wave of excess pressure.

I will now define what I mean by a plain mass. Consider a body of mass M to be acted upon by a force which causes it to vibrate in simple harmonic fashion, then if

s = amplitude of vibration

a = acceleration

t = time

f = frequency

the expression for the acceleration is:—

$$a = \frac{d^2s}{dt^2} = -4\pi^2f^2s$$

I define a plain mass as a body so supported and free from external or internal constraint that it would require a force of M times $4\pi^2f^2s$ to cause it to execute this vibration. A diaphragm of mass M does not in general for the purpose of this specification constitute a plain mass since any tones it possesses require much less force of the same frequency or nearly the same frequency to excite to a given amplitude than corresponds to the above formula. For the purpose of this specification the reaction of the supports necessary to maintain the mass in position relative to the other apparatus is neglected since the constraint is trivial compared with the inertia of the mass itself. A plain mass has now been described technically; it will be observed that it does not preclude a composite nature for the body employed.

Mathematically if the mass is acted upon by the pulsatory force of sound the amplitude of vibration to each harmonic is inversely proportional to the square of the frequency of the particular harmonic, and the maximum velocity attained is inversely proportional to the frequency, hence the E. M. F. generated in the coil falls uniformly as the frequency rises. If now this E. M. F. is applied to an apparatus capable of enlarging every harmonic in the proportion of its frequency the root mean square value of the current or potential so attained is a constant quantity. The harmon-

ics referred to are harmonics of pressure on the body. At this stage it may be observed that without any modification the coil generates true electrical equivalents of the ordinate of particle displacement.

- 5 Preferably the detector so defined is modified so that although the actual body vibrated may not in fact be free from mechanical tones in effect it behaves as though it were. Thus
- 10 10 the coil is no longer attached to a heavy inert body but instead is wound pancake fashion, that is a single or multi-layer spiral, the turns of which are bonded together with gum, shellac, or other binding material. With advantage
- 15 15 the magnetic air gap can be made large and might be six centimeters or even more. The coil is either hung in the gap or fastened across it by tissue paper or other tenuous membrane. Two definite conditions arise and
- 20 20 an intermediate stage. In the first place if the weight of the coil is so great that next to no sound is transmitted by it to the air beyond, the voltage generated is the equivalent of the displacement curve; in the second place if
- 25 25 the coil is so tenuous, it might be composed of gold leaf, that it does not sensibly obstruct the sound the excess pressure wave is reproduced; in the third place if the coil is of intermediate weight then for high frequencies
- 30 30 the displacement wave is represented, for low frequencies the excess pressure wave is represented, while for intermediate frequencies something between the two occurs. Any overtones in a coil used in this fashion must
- 35 35 in the main be obliterated by the averaging process which takes place, that is why the coil acts as a body devoid of overtones and conforms to the idea of a plain mass.
- 40 40 An apparatus with the property of enlarging every harmonic in proportion to its frequency, that is of obtaining the electrical equivalent of mathematical differentiation, can be constructed in the following fashion. Let the E. M. F. generated in the detector coil
- 45 45 be applied to the grid of a thermionic valve, or any distortionless electric relay, and let a small inductance be placed in a plate circuit; then the potential developed on the inductance will be the differential of the grid voltage.
- 50 50 Care would of course be taken to avoid the use of any iron core in such fashion as to distort the result by the influence of hysteresis or eddy currents. A device of this nature cannot be loaded or in other words cannot
- 55 55 supply more than a trivial amount of current without vitiating the conditions; it is the equivalent of a current transformer on open circuit and a valve so used is one used inefficiently or wastefully in the amplifying sense.
- 60 60 So much for the detection aspect of the subject. I now turn to the converse, the derivation of mechanical vibration from electrical vibration or voice currents. The principles involved are very similar. I presume in the
- 65 65 first place that true voice currents are re-

quired to be represented by the displacement of a plain mass, an inert coil carrying a sapphire engaged with a wax surface of sufficient softness not materially to interfere with the vibration which would be induced in the mass 70 in the absence of the wax. By wax is meant the usual composition employed in the production of master records.

The coil is simply floated on the wax surface for vertical or phonograph recording 75 and suitable modifications are introduced to meet the needs of the lateral or gramophone cut. Such a coil when supplied with currents properly representing the voice, musical performance or telephone message it is desired to 80 record does not vibrate in a manner truly corresponding to the electrical variations but on the contrary the wave form of the vibration of the coil differs from that of the electrical current passing through it in a very definite 85 manner; neglecting the resistance of the wax to penetration the harmonics are reduced in value in the proportion of $1/f^2$, that is, they are represented in a manner inversely proportional to the square of the frequency. Hence 90 in my invention the electric currents are in effect distorted artificially before they are supplied in the coil. The correct modification is that the harmonics are magnified in the proportion of the square of the frequency, 95 which change is brought about by the use of condensers or inductances in the following fashion. Supposing the electrical variations available can supply no appreciable power they are in the first place magnified by a thermionic valve relay or the like the last valve of which is fairly powerful. A small inductance is placed in the plate circuit of this latter valve and the variation of electrical potential on this inductance is the differential of the 100 current in the plate circuit so that every harmonic is exaggerated in proportion to its frequency. For this to be realized in practice the resistance of the plate circuit must be large compared with the impedance of the inductance used for the frequency considered. The potential across the inductance is now caused to operate a second valve also with a small inductance in its plate circuit; the variation of potential on this second inductance is the differential of the plate current and hence every harmonic is exaggerated in the proportion of its frequency, so that the variations of potential on this second inductance referred to the 105 original supply of current produced by the voice are exaggerated in the proportion of the square of the frequency. Again these variations are caused to operate a third valve designed to supply current to the recording coil. The term "coil" is to be understood in a broad sense; it may not involve a complete turn if a current transformer is used. A Fessenden vibrator (described in Patent No. 1,167,366) might conceivably be adapted to 110 the case.

Among resistances that may be encountered in apparatus for recording on wax may be mentioned, firstly, a thrust from the wax varying with and for small displacements 5 proportional to the departure from the mean position; secondly, a resistance of the nature of viscosity, a resistance depending upon the velocity of the moving parts; thirdly, the inertia of the recording element itself. Of 10 these resistances which comply with the conditions requisite for a damped tone, the first only modifies in scale the true voice current itself, the second can be corrected by an appropriate fraction of the differential of the 15 voice current, the third by the second differential of the voice current. In the practice of the invention, however, the inertia of the engraving element constitutes so large a proportion of the total resistance that for 20 most purposes it is not necessary to make any provision for any other resistances. Nevertheless if desired such compensation can be incorporated in the system.

Just as in the case of the detector the recording coil behaves as a plain mass and not as a resonator as is the diaphragm of a telephone or the like. A vibrating element of 25 this character is never used in practical telephony or sound recording for two reasons. 30 In the first place it is insensitive, and secondly it distorts the sound. By the use of relays of distortionless character now available the objection as to sensitiveness disappears; and by suitably modifying the wave 35 form of the currents before allowing them to vibrate the coil the distortion is eliminated.

The point of view adopted is that in all cases the mass of the detecting or inscribing agency is compensated for completely regardless of the frequency; while elastic control or viscous damping are either, and preferably, made relatively negligible or are provided for by appropriate currents derived from the sound. Thus if the natural period of the 40 engraving instrument corresponds to 250 vibrations a second, and should that be the only period which can be readily excited by the electrical forces brought to bear, at a frequency of 1000 vibrations a second the mass 45 is largely the predominant factor and so determines the extent of the vibration and the electrical forces are artificially distorted to ensure that the mass will vibrate over the proper range notwithstanding that the frequency is much above the natural frequency 50 of the instrument. The principle for dealing with any tone which occurs in the apparatus 55 consists in reducing the electrical forces at the resonance point to the amount required 60 to overcome the damping only.

Suppose a detector which derives current or potential from the sound equivalent to the excess pressure wave be available. Alternatively let a detector expressing the displacement wave be available and subject its

potential to a process of differentiation so as to derive a result equivalent to the excess pressure wave. Let this detector control an amplifying valve in whose plate circuit is placed a large inductance in parallel with a 70 combination of a small inductance, a condenser and a resistance, all in series, and so proportioned as to be the electrical equivalent of the mechanical vibrating system. By 75 this I mean that the time period is the same and the damping of the same degree. The impedance of the electrical system must be sufficiently small as to permit the changes in valve current to be driven through without sensible modification. With this state of affairs 80 the potential across the combination is such as to compensate for the mass, elasticity and damping of the mechanical system for any frequency up to that when the impedance of the electrical combination becomes comparable with the resistance of the valve itself. In 85 relation to the displacement wave of the sound the potential across the condenser, the resistance and the inductance respectively, is the equivalent of the unaltered wave, the 90 first differential and the second differential respectively.

The velocity attained by the mechanical system at any instant is the mechanical equivalent of the plate circuit current and hence 95 the amplitude developed is the integral of that current with respect to time and therefore corresponds to the displacement curve of the sound. At the resonant frequency the voltage across the condenser is equal and opposite to the voltage across the inductance and therefore the only potential supplied to the grid of the next valve is the potential across the resistance which is adjusted to compensate for the damping of the mechanical system. Additional damping could be provided by means of a supplementary coil attached to the main coil and more or less shortcircuited. 100

The reason for paying attention to the 110 case of a system with one damped tone is because the usual vibrating device occurring in telephony comprises a magnet and armature together with a coil for varying the strength of the poles telephonically. For 115 reasons of stability considerable elastic control must be provided otherwise the armature simply flies to the pole or poles. By taking into account this control such a device could be operated on the lines of my invention. An example is furnished in Figure 11 120 of the drawings filed with this specification. Possibly by careful experimental study of a reed or diaphragm telephone receiver such an instrument could be improved as a recorder by compensating for each of its tones so as to render the resonant action more uniform. 125

The recording element most favoured at the present time is a small compact coil weigh- 130

ing about 5 grammes adapted for torsional vibration located in a single magnetic air gap (induction density about 15000 c. g. s. lines), that is, without iron armature. The coil is under weak elastic control purely for facilitating the use of a gravity method of determining the depth of cut in the wax. In place of the ordinary telephone currents providing a link between the detector and the recorder it is obvious that the detector may control directly or indirectly a high frequency transmitting set similar to any used for wireless telephony and so modulate a carrier wave but inasmuch as the modulated carrier is rectified before operating the recorder and therefore becomes a telephone current no description of such matters is included in this specification. In fact the recorder could register messages or musical selections transmitted by wireless telephony from distant countries or from modulated carrier currents transmitted by means of wires. Apart from the subject matter of this invention, however, all such apparatus and schemes are dealt with in books on wireless telegraphy.

I have now described both the detector and the recorder separately and I now turn to their use in combination. The standard of reference adopted has been the wave of excess pressure. Particle displacement as well as pressure difference over a small interval can be derived from the wave of excess pressure by a process of integration or differentiation as the case may be. The detector described with reference to Figure 2 takes the excess pressure as the standard. It has been observed that if the process is stopped at the stage when the mass is exposed on one side only to the wave of excess pressure and simply carries a coil immersed in a magnetic field, then the E. M. F. induced is in terms of particle displacement. Recordings intermediate between that of full excess pressure and particle displacement can be obtained by the use of an inductance in one or other of the distortion circuits, which inductance tends more and more merely to check the current as the frequency rises and not to differentiate. These remarks are made because in making a record it may be necessary to take some account of the natural characteristics of the machine on which it is intended to reproduce it. My invention enables the operator to compensate for various influences which would otherwise impair the fidelity of the reproduced sound.

Of course if the characteristic of the detecting or reproducing agency supplies one or more of the steps required by my system as described then such step or steps would be omitted. In other words if it is not desired to record accurately the voice currents or potentials available but some modification thereof the invention is varied accordingly; in fact in the making of a sound record the

effect obtained necessarily involves the combination of the detecting, engraving and reproducing instruments. In particular should the phonograph or gramophone tend to give undue prominence to a harmonic of a particular pitch such a harmonic could be taken account of in the recording by shunting one of the valve transformers with an oscillation circuit which at the particular frequency reduces the efficiency of transformation.

From the point of view of the deficiencies of a given sound reproducing machine or phonograph, the recording which in combination with the machine gives a faithful reproduction of the original sound may not itself represent anything very definite, which is really another way of saying that the art must remain experimental until standarized. Apart then from permitting an engraving to be made equivalent to, say, the displacement wave, that is, an engraving with a well understood meaning, the system provides scope for a wide range of tone control. Any derivative of the excess pressure wave either by integration or differentiation is theoretically obtainable and also intermediate stages.

Although I have described recording apparatus using throughout the principle of the plain mass or non-resonant system cases may arise where the very great sensitiveness inherent in the combination of a microphone and sound concentrating trumpet presents great possibilities. By care and experiment such apparatus can be made to yield most useful results and in combination with a plain mass recorder as described such results can be engraved accurately on the wax.

Similarly it may happen that it is desirable to use the detecting part of the invention in conjunction with any recording telephone.

My invention is illustrated by the accompanying drawings. Figure 1 is an elevation in part section of a non-resonant detector. Figure 2 is a fragmentary view in part section of a non-resonant detector and a diagram of connections. Figure 3 is a rear elevation of a non-resonant sound detecting element with attached coil. Figure 4 is a fragmentary sectional view of a non-resonant detector showing a variation in construction. Figure 5 is a side elevation of a non-resonant recorder with stationary armature. Figure 6 is a fragmentary view in part section of a non-resonant recorder with annular magnetic air gap. Figure 7 is an inverted plan of the apparatus illustrated in Figure 6. Figure 8 is a diagram of connections applicable to recording the vibration of a sensitive liquid jet. Figure 9 is a diagram indicating a method of making a disc record using a non-resonant electro-magnetic detector and a non-resonant electro-magnetic recorder. Figure 10 is a fragmentary section of a detector with pancake coil of wire which detector is in effect non-resonant. Figure 11

is a diagram showing the invention applied to apparatus of the Bell telephone receiver class so as to convert it into a recording device which is in effect non-resonant. Figures 12, 13 and 14, illustrate recording apparatus with single magnetic air gap and gravity adjustment. Figure 12 is an elevation, Figure 13 an inverted plan and Figure 14 a plan. Figure 15 is an enlarged section 10 of a recording coil.

Figure 1 shows a plain mass 1 of composite construction built up from a disc of ebonite 2, a sheet of india rubber 3 and more ebonite 4 cemented together; a former or frame 5 carries a coil of wire 6 immersed in the field between the poles 7, 8 and 9, of the electromagnet 10 with a winding 11. The plain mass 1 is supported by ligaments, light springs or the like, in an aperture in a wall 12 shown in section from which it is separated by a space 13 usually made very small. To operate the apparatus sound is produced on the side of the wall remote from the electromagnet. A convenient arrangement is to 25 make the wall 12 a division between two rooms, one the recording room and the other the instrument room. A horn or trumpet may if desired be used to concentrate the sound waves upon the mass 1.

Figure 2 is a fragmentary view in part section of the elevation of Figure 1. The ligaments 14 attached to projections 15 in the wall and plain mass respectively are shown supporting the mass. Terminals 16 receive 35 wires from the coil 6. Across these terminals are placed a non-inductive resistance 17 and a condenser 18. Between the terminals 19 is felt the voltage variation across the non-inductive resistance 17. A number of valve 40 relays in cascade are interposed between the terminals 19 and the terminals 20 so that the plate current in the last of the series is carried by the wires from the terminals 20 and this plate current is an enormous magnification 45 and replica of the potential across the terminals 19; this plate current is caused directly or indirectly to operate a receiving or recording telephone.

Figure 3 is a view of the coil 6 wound on its former 5 at the rear of the plain mass 1. The poles 7, 8 and 9, of the electromagnet are indicated by dotted lines. Of course the former and coils move with and therefore add to the mass of the primary detector 1.

Figure 4 is a modification of the apparatus represented in Figure 1. Here the poles 7 and 8 of the electro-magnet are of the peg and ring type, that is, the pole 7 encircles the pole 8 and the field is radial. In this construction the pole 7 is built into and forms part of the recording wall 12. The primary detector or plain mass 1 is of conical shape and made from ebonite; the coil 6 is wound on the periphery of the detector.

Figure 5 shows a recording coil 1 to which

is attached a fin 2 carrying a recording jewel 3 engraving a blank cylinder 4. The coil is pivoted at 5 to a soft iron armature 6 which is situated between the poles of an electromagnet 7 energized by a coil 8. The currents supplied to the coil cause it to vibrate in angular fashion about the axis 5 in a manner very similar to the oscillation of a moving coil galvanometer. Flexible leads or mercury contacts convey the voice currents to the coil 75. 1. The mean depth of cut may be determined by a steady current in the coil, by a supplementary winding attached to and vibrating with the main winding, or by a spring control weak enough not to introduce an acoustic 80 tone into the system, a fine wire in torsion is very suitable.

Figures 6 and 7 show a circular coil 1 immersed in the field between the poles 9 and 10 of an electromagnet. To the coil is secured a cone or dome shaped attachment 11 for transmitting the vibration from the coil to the jewel 3 connected to the lever 12 pivoted at 13. The pressure on the blank is either the weight of the coil and attachments or 90 this is assisted or checked by a steady current in the coil, a supplementary coil with a steady current or by a spring.

Figure 8 is a diagram of connections. In this case it is desired to record accurately the 95 voltage variation of the sensitive jet microphone 14 comprising an insulating plate 15 and two electrodes, one a ring 16 and the other a rod 17. Current for the microphone is supplied by the battery 18. A non-inductive resistance 19 is inserted in the microphone circuit. When the jet ripples in response to vibration the resistance of the nappe or portion included between the electrodes 20 varies and therefore a corresponding change of potential 100 occurs across the resistance 19 which variation of potential causes a current to flow into the condenser 21 and through the resistance 22. The resistance 22 is sufficiently small not seriously to disturb the condenser current. Again the variation of potential across the resistance 22 causes a smaller current to flow 105 into the condenser 23 which in turn causes minute variations of potential across the resistance 24; this latter variation is highly 110 magnified by the relay 25 and converted into electric currents to operate the recording coil 1. To avoid using a large number of turns on this coil the current is transformed by the transformer 26. If desirable a variable high 115 resistance 27 may be disposed as shown so as to constitute a leak of current on the jet microphone which current does not depend on the frequency for the purpose of overcoming the resistance of the wax blank to impression.

Figure 9 illustrates another aspect of the invention; here it is desired to record sound in the form of a lateral cut on a disc blank 28 from the vibration of the plain mass 29 freely suspended by ligaments as at 30 due to the 120

direct action of the sound on the said mass when obstructing the aperture in the massive wall 31. A coil 32 is vibrated by the mass 29 between the poles 33 and 34 of an electro-magnet. In this example the variations which are necessarily feeble are in the first place magnified by the valve relay 37 comprising the usual elements, namely, a filament 38, a grid 39, a plate 40 and, say, an inductance 41. In practice probably six valves in cascade would be required in place of the single valve 37 but the diagram has not been complicated by the illustration of a multiplicity of valves or by the filament batteries. The electrical effects having been amplified by the relay 37 are then caused to operate the relay 42, in the plate circuit of which is placed a small inductance 43. The variation of potential across the inductance 43 is in turn amplified by the valve 44 in whose plate circuit is also placed a small inductance 45. It will be understood that the figure is diagrammatic only. Filament and high voltage batteries are omitted, according to common convention; also intervalve transformers in their complete form, all these being matters of ordinary practice and well understood. Valves 46 and 47 similar to valve 37 augment the current sufficiently to provide the relatively large electromechanical forces required to vibrate the recording element 1 shown pivoted about the axis 13 and immersed in the field between the poles 9 and 10 of an electro-magnet. The stylus 3 is shown in process of engraving the disc. Assuming the resistance to the motion of the coil due to the engagement of the cutter with the wax to be proportional to the instantaneous velocity of the cutter a fraction of the current which is the first differential of the true acoustic electric potential may be magnified and supplied to the coil without further differentiation for the purpose of compensating for this resistance. The diagram has not been complicated by the addition of this refinement which is within the competence of any one versed in the art to supply.

Figure 10 is a view of a primary detector constructed according to the invention. In the annular space between the poles 33 and 34 of a powerful electromagnet is located the detecting coil 29, 32, mounted on the tissue paper or indiarubber membrane 49. As a refinement a similar or approximately similar coil 50 is mounted on the ebonite ring 51 perforated with holes 52. The coils 29, 32 and 50, are connected in series or parallel in such manner that the inductance of the two coils becomes practically nothing as in Dr. Drysdale's wattmeter (see "Alternating Currents"—Hay, 1907). The coil, however, only has to supply the grid current and as that is usually very small indeed the compensating coil is not essential. Sound is produced on the side 65 of the wooden wall 31 remote from the mag-

net, which wall 31 may be one side of a box enclosing the apparatus or simply a partition between two rooms. A rubber ring 521 intervenes between the encircling pole 33 and the partition 31. The detecting coil 29, 32, responds to the pressure wave and generates E. M. F. proportional to the ordinate of the displacement wave of the incident sound. This E. M. F. is brought to the terminals 35 and 36. 75

Figure 11 is a diagram illustrating the principle of the invention as applied to a mechanical engraving system possessing as near as may be one tone and applied to a mechanism of the Bell receiver class adapted to the case. The figure is in diagram only, filament and high voltage batteries being omitted to avoid complication. A detector with sensitive element 29, 32, controls the valve 42 in the plate circuit of which is placed an inductance 43 with iron core 53 and secondary winding 54 which transfers the potential variations with or without alteration of scale as circumstances allow to the valve 44 in the plate circuit of which is placed an inductance 45, a resistance 55 and a condenser 56, all in series and in parallel with the primary of a potential transformer 57 controlling the valve 46 which valve operates the coil 58 of the electromagnetic engraving instrument through the transformer 59. The engraving instrument comprises a permanent magnet 60 of the horse shoe type with laminated poles 61 and laminated armature 62 shaped so as to be as free as possible from tones likely to interfere with the recording and constrained by two wires 63 separated by the width of the armature and by the rubber pad 64 to which one end is cemented. The magnet is carried by the ebonite bracket 65 pivoted at 66 to a feed-screw carriage not shown and counterbalanced to secure the proper gravitational pressure on the stylus 3, shown engraving the disc 28. An adjustment block 67 elastically hinged at 68 permits the distance of the armature from the poles to be varied. 100

It is to be understood that the wires 63 are stretched by the magnetic force and that the natural period is largely determined by these wires. For the system to be practicable it is necessary for it to have a frequency of the order of one thousand cycles a second though the best pitch is a matter for experiment and varies according to the proportion adopted. At this natural frequency the electrical system 45, 55 and 56, only allows the transformer 57 to supply the damping losses. 115

Conceivably if the armature were a diaphragm with N tones in an important acoustic region N systems in N valve transformers corresponding to 45, 55 and 56, or possibly in parallel could be incorporated in the scheme. Again if in place of the magnet and armature an engraving device as in Figures 120 125 130

12, 13 and 14, of this specification be used the effect of undue resonance of the reproducing machine could be checked in like manner.

Figures 12, 13 and 14, deal with a recording apparatus ready for lowering on to the cylinder 4 comprising a coil 1 elastically pivoted on the axis 5 by means of the wire 69 of which the coil is wound or if this is either too thick or too thin by a separate wire. A cutting stylus 3 is attached to the coil. At Figure 12 is shown an elevation of the apparatus engraving a cylindrical blank. The wire 69 is knotted or otherwise enlarged at 70 so that the screwed ebonite brushes 71 situated in the ebonite lever 65 pivoted at 66 can be used to tension the wire 69 and cause it to press tightly against the rubber pads 72 cemented to the lever 65. A counterbalancing adjustment is provided at 73. Figure 13 is an inverted plan of the apparatus in position between the poles 9 and 10 of an electromagnet. A plan from above is depicted at Figure 14. Wires from the end 70 of the coil lead to the mercury pools 74 and 75 into which the distorted telephone currents are led by the conductors 76 and 77.

Figure 15 is a greatly enlarged transverse sectional view of a recording coil for recording on a disc blank 28. The coil is situated in the magnetic air gap between the poles 9 and 10 of a powerful electromagnet. The field strength would be about 15000 c. g. s. units. To strengthen the coil the turns of which are bonded together with shellac or other binding material the central space is in part blocked in with wood or pitch 78. A central fin 79 carries the V-shaped recording jewel 3. If the effective length of the winding is 400 cms. and the maximum transformed current is 1 ampere, the force on the coil is approximately 300 grammes on each side.

While I have described my invention as applied to a sound recording system it is obvious that the invention is equally applicable to systems for reproducing sound, and wherever I have referred in the claims to a system of the class described, I have intended to include both sound recording and reproducing systems as my system may reproduce sound by the substitution of a sound reproducer for the recorder element.

Divisible subject matter not claimed herein is claimed in my copending applications Serial No. 30,605, filed May 15, 1925, entitled "Means for recording sound," and application Serial No. 284,587, filed June 11, 1928, entitled "Reproduction of sound"; in my Letters Patent No. 1,639,713, dated August 23, 1927, entitled "Reproduction of sound"; and in my application Serial No. 319,299, filed November 14, 1928, for "Reproduction of sound."

What I claim is:

1. In a system of the class described, a non-

resonant primary detector, means for obtaining a potential from that detector and means for obtaining a potential corresponding to the first, second or a higher differential of the potential derived from the detector.

2. In a system of the class described, a non-resonant primary detector and valve circuits arranged to yield potentials or currents which represent the first, second or higher differentials of the potential or current yielded by the detector.

3. In a system of the class described, a non-resonant primary detector in combination with a thermionic valve in the plate circuit of which is placed an inductive device the impedance of which is small compared with the impedance of the valve for important acoustic frequencies.

4. In a system of the class described, a non-resonant primary detector in combination with a thermionic valve in the plate circuit of which is placed a transformer the effective inductive impedance of which is small compared with the plate circuit impedance for all important acoustic frequencies.

5. In a system of the class described, a non-resonant primary detector and two valve circuits connected by transformers whose inductive impedance is small compared with that of the several plate circuits.

6. In a system of the class described, a non-resonant primary detector and a valve circuit capable of producing from the detector a mixture of the original potential and one or more differentials in desired proportions.

7. In a system of the class described, a material body free from natural frequencies over the important acoustic range, a winding arranged to move with the said body and supported in such a way as to constitute a plain mass, means for producing a magnetic field engaging with the winding and one or more valve circuits adapted to modify the electrical effects due to the movements of the winding.

8. In a system of the class described, a material body free from natural frequencies over the important acoustic range, a winding arranged to move with the said body and supported in such a way as to constitute a plain mass, means for producing a magnetic field engaging with the winding and means for obtaining a potential which is the first, second or higher differential of the electrical effect due to the movements of the winding.

9. In system of the class described, the combination of microphonic means comprising a sound responsive body free from natural tones within the important acoustic range and freely supported, detecting means for obtaining electric potentials which vary with the movement of said body, with a thermionic relay having in its circuit means arranged to increase the potentials obtained from the

said detecting means in proportion to the frequencies of the said potentials.

10. In means for recording sound, the combination of a primary detector which is itself 5 intrinsically non-resonant, means for obtaining an electric potential which varies with the movements of the detector due to the incidence of sound waves, means for producing current controlled by said potential and an 10 electro-mechanical recording device characterized, in that the moving part or parts thereof have no elastic restraint capable of imparting resonant properties to the said part or parts, which recording device is 15 adapted to be operated by said currents.

11. In means for recording sound, the combination of a non-resonant primary detector itself intrinsically non-resonant and which constitutes a plain mass, means for obtaining 20 an electric potential which varies with the movements of the detector due to the incidence of sound waves, means for producing currents controlled by said potential and an electro-mechanical engraving device characterized, in that the moving part or parts thereof have no elastic restraint capable of imparting resonant properties to the said part or parts, which engraving device is 25 adapted to be operated by said currents.

30 12. In means for recording sound, the combination of a substantially non-resonant detector for sound waves, means for producing an electric potential varying according to the sound waves, and a recording device comprising a compact vibrating element free from external control and friction and determining substantially by mass alone the amplitude of its vibration due to an electromagnetic impulse supplied from said non-resonant 35 detector.

40 13. In means for recording sound, the combination of a substantially non-resonant detector means for producing an electric potential varying according to the sound waves, means for distorting the variations of potential to produce a varying current, and a recording device comprising a compact vibrating element free from external control and friction and determining substantially 45 by mass alone the amplitude of its vibration due to an electromagnetic impulse supplied from said non-resonant detector.

50 14. In means for recording sound, the combination of means for producing an electric potential varying according to the sound waves, means for distorting the variations of potential so that every harmonic is enlarged in proportion of the square of its frequency to produce a varying current, and a recording device comprising a compact vibrating element free from external control and friction and determining substantially by mass alone the amplitude of its vibration due to 55 an electromagnetic impulse.

15. In means for recording sound, the combination of a primary detector in itself non-resonant and comprising a conductor vibrating in effect as a plain mass, means for producing a magnetic field engaging the conductor, a thermionic relay connected on one 70 side to the conductor, a coil in itself non-resonant connected to the other side of the relay and immersed in a magnetic field and an engraving stylus carried by the coil.

16. In means for recording sound, the combination of means in itself non-resonant for obtaining an electric potential from sound waves, and an electro-mechanical recording device comprising an element having no elastic restraint capable of imparting resonant 80 properties to said element and means for supporting said element for vibration about an axis.

17. In means for recording sound, the combination of means in itself non-resonant for 85 obtaining an electric potential from sound waves, and an electro-magnetic recording device comprising a mechanical vibratory element having no elastic restraint capable of imparting resonant properties to said element 90 and means for supporting said element for torsional vibration.

18. In means for recording sound, the combination of means in itself non-resonant for 95 obtaining an electric potential from sound waves and an electro-magnetic recording device comprising a vibratory element which is non-resonant, a floating beam, and means for supporting said element from said beam for torsional vibration.

100 19. In means for recording sound, the combination of means in itself non-resonant for obtaining an electric potential from sound waves, an electro-magnetic recording device which is in effect non-resonant and substantially free from static friction and is adapted to cut a sound groove in a wax blank and means for regulating the depth of cut in the wax.

110 20. In means for recording sound, the combination of means for obtaining an electric potential from sound waves, including a conducting sheet in effect non-resonant, means for producing a magnetic field, a plurality of valve circuits, transformers which couple 115 these circuits and the inductive impedance of the primaries of which is small compared with the internal impedance of the valves, and a electro-mechanical recording device in effect non-resonant.

120 21. In means for recording sound, the combination of means for obtaining an electric potential from sound waves, including a conducting sheet in effect non-resonant, means for producing a magnetic field, valve circuits 125 yielding various differentials of the potential derived from the conducting sheet in desired proportions, and a substantially non-resonant

conducting recording element immersed in a magnetic field and adapted to engrave a trace of its vibration on a record blank.

22. In means for recording sound, the combination of means for obtaining an electric potential from sound waves, including a conducting sheet in effect non-resonant, means for producing a magnetic field, valve circuits for differentiating and integrating the potential derived from the conducting sheet in desired proportions, and an electro-mechanical substantially non-resonant recording element adapted to engrave a trace of its vibration on a wax blank.
23. In means for recording sound, the combination of means for obtaining an electric potential from sound waves, including a conducting sheet in effect non-resonant, means for producing a magnetic field, valve circuits yielding various differentials of the potential derived from the conducting sheet in desired proportions, and an electro-mechanical recording element in itself non-resonant adapted to engrave a trace of its vibrations on a wax blank.
24. A non-resonant detector including means whereby a potential is derived from sound waves, means for amplifying the said potential, means for integrating such potential, and a non-resonant recorder operated by such integrated potential.
25. In combination a non-resonant primary detector, an electrical system connected with said detector for deriving a potential therefrom and means connected with said electrical system for obtaining a plurality of differential potentials with respect to the potential derived from the detector, and responsive means actuated by the differential potentials.

In testimony that I claim the foregoing as my invention I have signed my name this 29th day of October 1920.

ADRIAN FRANCIS SYKES.
